UNITED STATES PATENT OFFICE.

HARRISON V. APPLEY, OF BINGHAMTON, NEW YORK.

TRUSS.

1,072,804.

Specification of Letters Patent.

Patented Sept. 9, 1913.

Application filed July 1, 1912. Serial No. 706,990.

To all whom it may concern:

Be it known that I, HARRISON V. APPLEY, a citizen of the United States of America, residing at Binghamton, in the county of 5 Broome and State of New York, have invented certain new and useful Improvements in Trusses; and I do hereby declare the following to be a full, clear, and exact 10 description of the invention, such as will enable others skilled in the art to which it appertains to make and use the same.

My invention relates to improvements in trusses, and its object is to provide the same with improved means for adjustment; to 15 provide a device that will fit the person and be comfortable in use, and to provide the same with various new and useful features as hereinafter more fully described and particularly pointed out in the claims, reference being had to the accompanying drawings in which:—

Figure 1 is a perspective of a device embodying my invention. Fig. 2 is a plan view 25 of the front portion of the same. Fig. 3 an enlarged detail, in transverse section of the clamping means of the coupling. Fig. 4 an enlarged section of the pad and means 30 for holding and adjusting the same, and Fig. 5 a perspective detail of a portion of the device.

Like numbers refer to like parts in all of the figures.

To extend at each side of the body and support the device in place, I provide a pair of 35 curved and resilient or spring members 1—1 preferably of spring steel. These members are spaced apart more or less according to the size of the wearer, and at the rear are connected by straps 2 and a buckle 3, and at the 40 front are connected by elongated links 4 pivoted to the respective front ends of said spring members at one end and oppositely inserted in a flattened tubular coupling, and adjustable longitudinally in the coupling to 45 space apart, more or less, the front ends of said spring members to adjust to properly fit persons of different sizes. These links extend downward and forward from the front ends of the springs throughout about 50 one-half of their length and are bent to extend thence substantially horizontal into the coupling and these links and the coupling also have a suitable forward convexity. A pad 8 is adjustably mounted on either one 55 or both of the links (one being shown) and

carried on a ball 11 mounted on a tubular slide 9 adjustable on the link. The back plate of the pad is provided with a socket 12 adjustable on the ball. This socket is partially in the back plate and partially in 60 an inner socket member 12 spaced apart from the back plate and secured thereto by screws which may be tightened to clamp the ball in the socket and hold the pad adjusted.

The pad proper is formed of a concave 65 pad plate 13 and a facing of suitable material, such as leather, folded over the edge of the pad plate and secured thereto and is filled out convex with elastic filling and is thus rendered quite comfortable to the user, 70 which plate is preferably beaded on the edge to prevent cutting the facing, and to present a smooth rounded edge. The pad plate is detachably secured to the back plate by screws 14 whereby the same can be readily 75 detached for replacing the facing or filling 16.

To securely clamp the various parts screws are provided having truncated conical portions which extend through the links 80 and force the same apart and thus clamp the same between the screws and the surrounding coupling 5 or slide 9, such screws being shown in the coupling at 7 and in the slide at 10.

The ball is provided with a shank 17, which is inserted in an opening in the slide and also engages the link and thus aids in holding the ball and slide in fixed relation and also more securely clamps the parts in 90 place.

Where the links are hinged in the ends of the springs 1 shoulders 6 are provided which engage the links and limit the outward swing of the springs. Thus in adjusting the 95 device on the wearer the springs will yieldably embrace the body and hold the device in place when the straps are disconnected at the rear.

What I claim is:—

1. A truss comprising curved side members, an adjustable flexible connection between the rear ends of said members, links pivoted to the forward ends of said curved members, each having portions extending 105 diagonally forward and downward and thence horizontally each of said links embodying spaced parallel members, and a coupling connecting the outer ends of the links.

2. A truss comprising comparatively nar- 110

row side members, means adjustably connecting the rear ends of said side members together, the forward ends of said members being notched to provide shoulders, links pivoted to the forward ends of said members and engaged by the shoulders on said members to limit the outward movement of said members, and a coupling adjustably connecting the links.

10 3. A truss comprising side members, means connecting the rear ends of said members, links pivoted to the forward ends of the said members, each including spaced members, and a coupling embracing the said links and including means to wedge between the spaced members of the links to couple the links together.

4. A truss, comprising a link, a member surrounding the link and adjustable thereon, a screw extending through said member and the link; and having a truncated conical portion within the links to wedge the same

apart and clamp the same within the member.

5. A truss, comprising a tubular coupling, 25 links adjustable in the coupling and a screw in the coupling having a truncated conical portion within the link and acting to clamp the link within the coupling.

6. A truss, comprising a link, a slide adjustable on the link, a ball carried by the slide, a pad supported on the ball and having a socket adjustable on the ball, a screw extending through the slide and link and inserted in the ball, and also having a truncated conical portion engaging the link to clamp the same within the slide. 30 35

In testimony whereof I affix my signature in presence of two witnesses.

HARRISON V. APPLEY.
